UNITED STATES PATENT OFFICE.

HERMAN G. PAPE, OF NEW YORK, N. Y.

COMBINED TELEGRAPH AND TELEPHONE INSTRUMENT.

1,270,861.

Specification of Letters Patent. Patented July 2, 1918.

Application filed February 1, 1915. Serial No. 5,384.

To all whom it may concern:

Be it known that I, HERMAN G. PAPE, a citizen of the United States, and resident of New York, in the county of New York and State of New York, have invented a certain new and useful Combined Telegraph and Telephone Instrument, of which the following is a specification.

My invention relates to a sound reproducing instrument designed for use either as a telegraphic instrument or a telephone receiver, and is particularly adapted for use in place of the ordinary "sounder" such as is commonly used in the well known "Morse" telegraph system.

In accordance with my invention, an instrument which may outwardly resemble a telephone instrument such as used by telephone operators, is adapted to be held against the ear and comprises means for reproducing telegraph signals which are heard as single taps or clicks substantially like the sounds produced by an ordinary Morse sounder. As the sounds are clearly audible only to the person wearing the instrument, the noise of the usual sounder is eliminated. This feature renders the invention of special value for use in telegraph offices or rooms where a number of sounders are employed. In such situations, the noise of a number of instruments in operation at the same time results in confusion and renders it necessary for each operator to have a shield or sound director for his own instrument in order to distinguish it from the other instruments. By the use of the present invention the noise and confusion is eliminated, and each operator hears his own "sounder" or receiver without distraction.

An object of the invention is to produce a therapeutic telegraphic ear sounder, one which will produce exhilarating instead of aggravating and sense dulling waves.

A further feature of the invention is the provision of sound amplifying and directing means for use in combination with the sounder and to which the sounder may be connected at will to permit the sounds to be heard at a distance. Thus, for example, in a railroad station where the ticket agent is also the telegraph operator, the "sounder" may be worn on his head while he is receiving the telegraphic messages, and when through, or at any time he may remove the

sounder from his ear and connect it to the sound amplifying device. He is then free to attend to other duties, and any signal or message coming over the line, and reproduced in the sounder can be heard in any part of the room, the sound being magnified by the amplifier.

Another aim of the invention is the reduction of cost as compared with instruments now used for like purposes on standards, desks and tables.

In a practical embodiment of the invention, the sounder may comprise an electromagnet having a fixed continuous circuit or winding to be connected in the telegraph circuit in the same manner as the standard Morse ticker or sounder, said magnet having an armature suspended to vibrate in response to the electrical impulses set up in the magnet. A sound reproducing member, diaphragm, sounding piece or anvil is located adjacent a striker connected to the armature, so that the movement of the armature produced by an electrical impulse, causes the said striker to strike the diaphragm or anvil, resulting in a tap or click substantially like that produced by the ordinary Morse sounder. In order to prevent a continued vibration of the diaphragm, sounder, or anvil and consequent continuation or lengthening of the sound, an adjustable buffer is set against the diaphragm or anvil which permits only an instantaneous sound or vibration. Cork or other suitable material may be interposed between the said striker and the magnet armature to further aid in deadening any continued vibration of the magnet armature, and to secure an agreeable and not sharp or aggravating tick.

Suitable means may be provided, for adjusting said striker, to bring it in contact with the diaphragm and thereby convert the instrument into a telephone receiver capable of reproducing telephonically transmitted messages.

The sound amplifying device may comprise sound amplifying and reechoing bells or domes such as disclosed in my co-pending application Serial No. 879,012. The sound amplifying device may be mounted on a rotatable standard and tilttable to any desired angle on the standard so that the sound may be directed to any part of the room. The sounder may be quickly attached or re-

moved from the amplifying device, being held thereon by spring clips or other suitable means.

It is of course, not necessary to provide a sound amplifying device as disclosed in my co-pending application, cited. The outer chamber of my ear piece need only be made convex instead of concave, so as to constitute a typical trumpet bell similar in design to the ear piece in my co-pending application, Serial No. 80,874, and the deeper the bell, the more effective will be its augmentation, and although such a device might, like the stand shown in Figure 4, be permanently placed or fastened upon a table, desk or other support, it may be instantly used at the will of the listener, in absolute privacy, through the application of a form of ear tube thereto, like or similar to those shown in my Patent No. 789,876. Such tubes may, of course, be attached to any sound directing device, sound transmitter, sounding disk, sound box or the like, which may be the amplifier as here shown in Fig. 4, or any other more suitable amplifier or sound carrier, or even a sound-proof box or housing over a standard Morse type table ticker, without departing from the scope of my invention, as will be apparent by an examination of the appended claims.

Other features and advantages of the invention will appear hereinafter.

In the accompanying drawings Fig. 1 is an elevation view of a sound reproducing instrument constructed in accordance with the principles of my invention. Fig. 2 is an end view, the removable top or end 28 being removed. Fig. 3 is a sectional view as indicated by the line 3-3 of Fig. 1. Fig. 4 is a part sectional elevation of the sound amplifying and directing device with the receiving instrument or sounder attached thereto. Fig. 5 is a view of the sounder and means for attaching it to the amplifier as viewed from the right hand side of Fig. 4. Fig. 6 is an end view of the sounder with the ear piece removed.

The receiver or sounder comprises a disk, structure or casing 1 in which or to which is mounted an electro-magnet comprising a coil 2 and a shell 3 which may have a screw threaded connection 4 in a wall or partition 5 of the mounting, support or casing 1. Binding posts 6 for the ends of the magnet 5 coil are threaded into metal plugs 7 provided with terminal openings 8 for split pins or other terminals of the line wires. A cap or ear piece 9 is removably attached to the casing 1 by means of an annular flange or projection 10 externally threaded to engage corresponding threads on the casing 1. A threaded ring or nut 11 secures in position a diaphragm 12 preferably of metal, the periphery of which is located between a shoulder 13 formed on the casing and the

ring 11. Washers or gaskets 14 which may be made of paper or other suitable material are placed on opposite sides of the diaphragm between said shoulder and the ring 11. The pressure of the gaskets 14 may be regulated by rotating the ring 11 to any desired position of adjustment.

The cap or earpiece 9 is adjustable toward and from the diaphragm providing a focus regulation and is held against accidental displacement from its adjusted position by means of spring clip or tongue 15 secured as by a screw 16 to the cap. Said spring is adapted to seat in notches 17 arranged at intervals around the casing 1. Index numbers or other indicating characters 18 may be placed on the casing adjacent the notches 17 to indicate the position of adjustment, and enable the user after having once determined the most effective adjustment for any specific use, or best suited for his ear, to readily adjust the cap to such position at any time without further experiment. To prevent the cap 9 from being accidentally entirely unscrewed and disconnected from the casing 1 the latter is provided with an annular shoulder 15' in the path of the spring 15 which offers sufficient resistance to the removal of the cap to give warning when the cap is unscrewed beyond its normal range of adjustment.

The cap or ear piece 9 has a central opening 19 and an inner curved sound reflecting surface 20 which tends to focus or concentrate the sound waves at the center of the diaphragm from which point they are most effectively transmitted through the sound conducting opening 19. The surface 20 is surrounded by an annular depression or enlargement 21 of the sound concentrating chamber or opening between the diaphragm and cap 9, which enlargement forms a swell chamber or capacity chamber to divert or relieve the pneumatic pressure set up, preventing undue pressure on the ear drum of the operator, preventing din and fatigue and indistinct or muffled sounds. Kerfs 19^a, such as disclosed in my Patent No. 800,675, Oct. 3, 1905, may be formed in the outer face of the cap and extend radially outward from the opening 19. These kerfs form outlets to relieve the pressure in the sound concentrating chamber, and aid in producing clear and distinct sounds, and prevent undue pressure on the ear drum.

The electro-magnet is provided with an armature 22 suspended to vibrate in response to electrical impulses in the electro-magnet. The means for suspending the armature comprises a sleeve or hollow extension piece 23 connected to a supporting spider 24 which, as shown in Fig. 2, comprises radial arms integral with inner and outer rings 25 and 26. The sleeve extends through a central opening out of direct contact with the spider but

connected thereto through the medium of a cement 27 or other suitable material. The spider 24 is clamped between a ledge in the casing 1 and a removable end piece 28 having a screw threaded connection with the casing.

A striker 29, which may consist of a metal head or tip, is connected to the magnet armature through the medium of a cork or other sound deadening material 30 and a central rod 31 extending through a central opening in the magnet and connected to the sleeve 23 by the cement 27. The lower end of the rod may also be connected by cement 32 to a spider which may be of the same construction as the upper spider 24. The spider 33 is held in position between washers 34 having a screw threaded connection with the casing 1. The material 27 and 32 uniting the sleeve 23, rod 31 and upper lower spiders, may be the same as that set forth in my co-pending application Serial No. 874,234, and used therein for uniting the main diaphragm and electrode. Said spiders form an elastic support permitting the armature to move freely in response to electrical impulses and at the same time permitting adjustment of the hammer or striker 29 toward and from the diaphragm 12. Such adjustment may be effected by a plug 35 threaded into the top piece 28 and carrying a block 36 of felt or other soft elastic material which bears against the upper end of the rod 31 or sleeve 23. By screwing down the plug 35 the striker 29 is brought closer to the diaphragm and by screwing the plug outward, the striker and connected parts are lifted upward or away from the diaphragm by the resilient supporting spiders 24, 33. Blocks 37 of felt or the like bear against the spider 33 and together with the material 36 tend to prevent any continued vibration of the striker 29 so that when the magnet is energized the striker will give a single sharp blow to the diaphragm.

To prevent a continued or lengthened vibration of the diaphragm, a sound deadener or buffer device is provided to bear against the diaphragm. The specific form of such device may be widely varied, and as herein shown comprises a disk 39 of felt or the like, eccentrically mounted on the inner end of a light spring rod 40 extending through the casing 1 and provided externally on the casing with a thumb piece for rotating the rod or adjusting it longitudinally, and thereby adjusting the pressure and position of the buffer 39 on the diaphragm. A set screw 40 locks the buffer in adjusted position. It will be noted that with the buffer against the diaphragm the entire construction is designed and adapted for producing sharp, short sounds or clicks, substantially like those produced by the common Morse sounder, and in marked contrast to the humming

and poorly defined sounds produced in an ordinary telephone receiver by Morse code signals.

When the armature is operated by a magnetic impulse, the tapper produces a tap or sound on the diaphragm, and depresses and holds the same in a depressed state, until the circuit is opened or the current flow through the magnet coil shut off, when the armature and diaphragm return quickly to normal position, which action causes the diaphragm to render a second sound identical to that caused by said tap, the production of the two sounds in this manner being typical of and essential for producing the Morse type of signals.

By screwing down the plug 35 until the striker 29 engages and bears with a slight tension against the diaphragm, the instrument may serve as the telephone receiver as the diaphragm will then follow the movements of the striker and is thus capable of reproducing articulate sounds. Its action as a telephone receiver may also be improved by adjusting the buffer 39, away from the diaphragm.

The instrument is provided with a bail 41 and a spring clip or head piece 42 enabling the instrument to be attached to the ear of the operator in a well known manner. The adjusting plug or thumb screw 35 is held against accidental rotation from any adjusted position by a spring clip 36 secured thereto and adapted to seat in any one of a series of radial notches 37.

In Fig. 4 is shown a sound amplifying and directing device 43 to which the sounder may be attached for the purpose of magnifying the sounds so that they may be distinctly heard at a distance from the sounder. Said device may comprise an outer bell or dome having a rear opening 45 at which is connected a funnel or horn 46 through which the sound waves from the diaphragm 12 are directed and amplified, said sounds striking a deflecting surface 47 formed by an inner bell or dome 48. The sound reflected from the surface 47 is thrown rearwardly and again amplified and reflected on the surface 49 of the outer bell 44 and from thence again amplified as it is directed outwardly through the open mouth of the bell 44. The inner bell 48 is secured to the outer bell by brackets 50 and 51, and to the funnel 46 by brackets 52. These brackets serve the double function of rigidly uniting the parts and also preventing the bells or funnel from ringing. The sounder is removably attached to the amplifier by any suitable means such as spring clips 53 secured to the bell 44 and having their free ends curved to engage a shoulder 54 on the sounder and hold the latter clamped against the bell 44.

In order that the bell 44 may be pointed in any direction for directing the sound, the

device is mounted on a standard 55 rotatably supported on a stationary base 56 which may be attached by screws 57 to a table or other support 58. In order to hold the standard 5 against accidental rotation from any position of adjustment, a spring actuated holding pin 59 is mounted in a disk or support 60 fixed to the standard 55, said pin adapted to engage any one of a series of notches 61 placed at suitable intervals in the base plate 56. By withdrawing the pin 59, the standard 55 and amplifying device carried thereby may be rotated to point in any desired direction.

15 The sound directing device may also be tilted to any desired angle, and for this purpose is attached to the standard 55 by means of a bracket 62 fixed to the bell 44, and a pivot screw 63. The lower end of the bracket 20 62 is in the form of a segmental rack 64, held in any desired position of adjustment about the pivot 63 by a detent 65. The latter is held in engagement with the rack by a spring 66 and may be withdrawn from the 25 rack by means of a finger piece 67 to permit adjustment.

Various modifications may be resorted to without departing from the spirit and scope of my invention.

30 What I claim is:—

1. An electro-responsive sound reproducing instrument comprising an electro-magnet and its armature, said armature movable in response to magnetic impulses due to electrical impulses in the electro-magnet, a sounder or sound producing diaphragm, a striker carried by the armature in position to strike the sounder or diaphragm when the armature is actuated by a current impulse in the electro-magnet, and a sound deadening means interposed between the striker and the electro-magnet.

2. The combination with an electro-magnet, of an armature therefor movable toward and from the electro-magnet in response to magnetic impulses set up in the electro-magnet, a housing, a sounder or diaphragm, said armature and sounder or diaphragm located beyond the opposite ends 45 of the electro-magnet, a striker, a connection between the armature and striker for causing the striker to strike the diaphragm when the armature is actuated by the electro-magnet, and exteriorly adjustable means to 50 limit the operation of the striker to a single blow.

3. In an ear appliance, the combination with an electro-magnet, of an armature therefor movable toward and from the electro-magnet in response to magnetic impulses set up in the electro-magnet, a sounder or diaphragm, said armature and sounder or diaphragm located beyond the opposite ends 55 of the electro-magnet, a striker, a connection between the armature and striker for

causing the striker to strike the sounder or diaphragm when the armature is actuated by the electro-magnet, said connection comprising a rod extending through a central opening in the core of the magnet and connected at its opposite ends to the armature and striker respectively, and a resilient support by which the armature and striker are suspended and by which the striker is retracted and normally limited to a single blow.

4. The combination with an electro-magnet, of an armature therefor movable toward and from the electro-magnet in response to magnetic impulses set up in the electro-magnet, a diaphragm, said armature and diaphragm located beyond the opposite ends of the electro-magnet, a striker, a connection between the armature and striker for causing the striker to strike the diaphragm when the armature is actuated by the electro-magnet, and means for adjusting the striker toward and from the diaphragm, said adjustment permitting the striker to be adjusted into position to bear against the diaphragm, permitting the diaphragm to reproduce articulate sounds electrically transmitted to the electro-magnet, and also permitting adjustment of the striker into position to cause a single blow of the striker 95 against the diaphragm when the magnet is energized.

5. In a sound reproducing instrument, the combination with an electro-magnet, of an armature therefor, elastic means by which the armature is supported and permitted to move when attracted by the electro-magnet, said elastic means returning the armature when the magnet is deenergized, a sounder or diaphragm, a striker, a connection between the armature and striker for causing the latter to strike the sounder or diaphragm when the armature is actuated, a cushion forming a yielding stop determining the normal position of the armature and striker, and means for adjusting said cushion to adjust the striker toward or from the sounder or diaphragm.

6. In a sound reproducing instrument, the combination with an electro-magnet, of an armature movable to attracted position when the electro-magnet is energized, elastic means for returning the armature, a striker, a sounder or diaphragm, means for actuating the striker by the armature to cause the 115 striker to strike the sounder or diaphragm when the armature is actuated, and a cushion stop limiting the return movement of the armature from attracted position, and maintaining the armature under a continuous tension of the said elastic returning means, said cushion serving to prevent a continued or repeated operation of the striker when a single or momentary electrical impulse occurs in the electro-magnet.

7. In a sound reproducing instrument adapted to be applied to the ear, the combination with an electro-magnet, of an armature movable to attracted position when the electro-magnet is energized, elastic means for returning the armature, a striker, a diaphragm or sounder; means for actuating the striker by the armature to cause the striker to strike the diaphragm or sounder when the armature is actuated, the operation of the striker being normally limited to a single blow, a cushion forming a stop to limit the movement of the armature by said elastic means, and means for adjusting said cushion and thereby varying the normal position of the striker.

8. In a sound reproducing instrument adapted to be applied to the ear, the combination with a casing, of an electro-magnet and diaphragm or sounder mounted in the casing, an armature for the electro-magnet, a striker actuated by the armature to strike the diaphragm or sounder, and a spider comprising elastic arms supporting the armature and operable to return the armature and striker to their normal position of rest, said casing comprising a removable end plate by which the spider is clamped in the casing.

9. In a sound reproducing instrument, the combination with a casing, of an electro-magnet and diaphragm mounted in the casing, an armature for the electro-magnet, a striker actuated by the armature to strike the diaphragm, a spider formed of thin sheet material and comprising elastic arms supporting the armature and operable to return the armature and striker to their normal position of rest, the outer ends of said arms terminating in an integral ring connecting said arms, said casing provided with an annular supporting surface for said ring.

10. In a sound reproducing instrument, the combination with a casing, of an electro-magnet and diaphragm mounted in the casing, an armature for the electro-magnet, a striker actuated by the armature to strike the diaphragm, elastic arms supporting the armature and operable to return the armature and striker to their normal position of rest, a ring connecting the outer ends of said arms, said casing provided with an annular supporting surface for said ring; and the casing also comprising a removable end piece having a screw threaded connection with the body of the casing and clamping said ring against said supporting surface.

11. In a sound reproducing instrument adapted to be applied to the ear, the combination with an electro-magnet, of a casing in which the electro-magnet is mounted, a sound producing sounder or diaphragm, an armature for said electro-magnet movable in response to electro-magnetic impulses in the electro-magnet, a striker connected to

move with the armature, and positioned to strike the sounder or diaphragm when so moved, and elastic spiders mounted in the casing and positioning, supporting and guiding the armature and striker and operable to withdraw the striker from the armature, said spiders located at opposite ends of the electro-magnet, one spider being interposed between the electro-magnet and sounder or diaphragm.

12. In a sound reproducing instrument adapted to be applied to the ear, the combination with a casing, of an electro-magnet and a sounder or diaphragm mounted in the casing, an armature for the electro-magnet, a striker actuated by the armature to strike the sounder or diaphragm, a sleeve secured to the armature, a rod extending into said sleeve, said striker connected to the rod, a spider mounted in the casing to form an elastic support for the armature, and cement forming a connection between the spider and said sleeve and between the sleeve and rod, said cement adapted to be applied in a liquid or plastic state and self hardening to rigidly unite the parts.

13. In a sound reproducing instrument, the combination with a casing, of an electro-magnet and sounder or diaphragm mounted in the casing, an armature for the electro-magnet, a striker actuated by the armature to strike the sounder or diaphragm, an adjusting plug having a screw threaded connection with the casing and forming a means for adjusting the striker toward or from the sounder or diaphragm, a spring detent carried by the plug, the casing provided with an annular series of notches in which the detent is adapted to seat to hold the plug in its position of adjustment.

14. In a sound reproducing instrument, the combination with a casing, of an electro-magnet and sounder or diaphragm mounted in the casing, an armature for the electro-magnet, a striker actuated by the armature to strike the sounder or diaphragm, an adjusting plug having a screw threaded connection with the casing and forming a means for adjusting the striker toward or from the sounder or diaphragm, and a buffer of non-resonant material interposed between the plug and the armature and striker.

15. In a sound reproducing instrument adapted to be applied to the ear, a diaphragm, vibrative to reproduce articulate sounds, a striker arranged to strike directly against the diaphragm, and means independent of the mounting of the diaphragm to quickly reduce, limit, or check its vibrations and bring it to rest after being struck, whereby a single sound or click is produced.

16. In an electrical ear receiver, the combination of a sound producing diaphragm or sounding element, means to vibrate the diaphragm or sounding element, and a buffer

bearing against the diaphragm or sounding element, said buffer being adjustable along the surface of the diaphragm or sounding element toward and from the central point 5 of vibration.

17. In a single stroke, electrical ear ticker, the combination of a sound producing element or diaphragm, means to vibrate the diaphragm, and a buffer bearing against the 10 same, said buffer adjustable along the surface of the diaphragm toward and from its center and also adjustable to vary its pressure on the diaphragm.

18. In a sound reproducing instrument, 15 the combination with a casing, of an electro-magnet and sounder or diaphragm mounted in the casing, an armature for the electro-magnet, a striker actuated by the armature to strike the sounder or diaphragm, elastic 20 radial arms supporting the armature and operable to return the armature and striker to their normal position of rest, and cushions of soft resilient material against which said radial arms bear when in their normal 25 position of rest.

19. In an instrument of the class described, the combination of a housing, a diaphragm, said housing comprising an ear cap and a casing, said ear cap having screw 30 threaded connection with the body of the casing, a holding ring for the diaphragm, said ring and casing formed to provide an annular space to receive the periphery of the diaphragm, a washer or a gasket seated 35 in said annular space and forming a bearing for said periphery, said ring threaded in the casing and adjustable by rotation to vary the pressure of said washer on the diaphragm, the cap adjustable by rotation toward 45 and from the diaphragm, a spring detent connected to said cap, said body of the casing provided at intervals around its outer surface with notches to receive said detent and hold the cap in its adjustable position.

20. In an instrument of the class described, the combination of a casing, a diaphragm, said casing comprising a cap or end piece having a screw threaded connection 50 with the body of the casing, a holding ring for the diaphragm, said ring and casing formed to provide an annular space to receive the periphery of the diaphragm, a washer or a gasket seated in said annular space and forming a bearing for said 55 periphery, said ring threaded in the casing and adjustable by rotation to vary the pressure of said washer on the diaphragm, the cap adjustable by rotation toward and from the diaphragm, a spring detent connected to 60 said cap, said body of the casing provided at intervals around its outer surface with notches to receive said detent and hold the cap in its adjustable position, the casing being provided with an annular shoulder or 65 projection in position to engage said detent

if the cap is unscrewed beyond its normal range of adjustment and thereby prevent accidental removal of the cap.

21. An electro-responsive sound instrument comprising a casing, a sounding piece 70 therein, an ear piece adjustable toward and from the sounding piece, a holding clip brought into operation only when the ear piece has been moved beyond its normal range of adjustment, and means to prevent 75 the ear piece from being accidentally disconnected from the casing.

22. An electro-responsive sound instrument comprising a casing, a diaphragm 80 therein, a cap having a threaded connection with the casing and adjustable toward and from the diaphragm, said cap and casing provided with a spring clip and a series of detents to be engaged by said clip to hold the cap in adjusted position, and an annular shoulder to engage said clip and prevent the cap from being accidentally disconnected. 85

23. In an ear-applied electrical ticker or sounder, the combination with a sounding piece, of electro-responsive means to vibrate 90 or sound the sounding piece, and a buffer to normally bear against the same to prevent a protracted vibration or note, and means to adjust the pressure and position of the buffer on the sounding piece. 95

24. In a sound producing instrument, the combination with a diaphragm or sounder, of electro-responsive means to vibrate the diaphragm or sounder, a buffer to bear 100 against the diaphragm or sounder and prevent a protracted vibration, a structure to support the diaphragm or sounder, and means positioned externally of the casing to adjust the buffer and thereby regulate the pressure thereof against the diaphragm or sounder, said means also operative to adjust the buffer toward and from the center of vibration of the diaphragm or sounder. 105

25. In a combined telephonic and telegraphic sounder, a housing, a sounding piece, a tapper for the sounding piece for the reproduction of telegraphic taps, means to set the tapper with a tension against the sounding piece for the production of articulate sound vibrations or speech, said means 110 being adjustable from the exterior of the housing. 115

26. A telegraphic ticker in combination with a concussion or pneumatic impact diverting ear piece for the private delivery of 120 the telegraphic ticks to the ear of the listener, and adjustable means for converting the ticker into a telephone sounder or articulate speech reproducer.

27. An electric sound producing instrument, comprising a magnet, an armature therefor, a sounder, a tapper for tapping the sounder through actuation of the armature by the magnet, and means to cause the tapper to bear against the sounder and hold it nor- 125 130

mally in a state of tension, and thereby cause the sounder to follow any movements imparted to the tapper.

28. The combination of a vibratory or resilient sounding member for the production of telegraphic messages, resilient means carrying a tapping member or striker for striking the sounding member, a magnet, a coil, an armature for actuating the tapping member, and yielding means for adjusting or fixing the tapper with a tension normally

against the resilient sounding member, so that any movement of the tapping member is followed up by the sounding member.

Signed at New York, in the county of 15
New York and State of New York, this 21st
